Attorney

Patent laws of the United States and all countries of the world, and particularly the laws of the United States, do not give any right to the inventor to prevent others from making, using, or selling his invention, unless he has obtained a patent therefor. The inventor, however, may obtain a temporary right to prevent others from making, using, or selling his invention by applying for a patent. The inventor may also obtain a temporary right to prevent others from making, using, or selling his invention by applying for a patent, and then, if the patent is granted, the inventor may prevent others from making, using, or selling his invention by the use of the patent rights.

UNITED STATES PATENT OFFICE

2,520,319

HAT BLOCKING APPARATUS

Joseph Luckow, New York, N. Y.

Application August 7, 1947, Serial No. 766,988

3 Claims. (Cl. 223—15)

1

The present invention relates to the art of hat blocking, and, particularly, to improvements in hat-blocking apparatus.

The invention contemplates novel, simple, rugged, and inexpensive apparatus arranged to apply and to maintain pressure upon a plurality of hat blocks between which a hat blank or like piece of felt or other material is inserted for the purpose of forming the same as a result of drying while under pressure between such hat blocks.

As is the well-known custom in the hat trade the blanks, often of felt, are placed between forming blocks after the blank has been suitably steamed, and these blocks are brought together under considerable pressure with the blank between them, the pressure being often derived from a weight set upon the uppermost block. A variation of the practice is to clamp the blocks together with the steam-softened blank between them, and to permit the blank to dry, and so become permanently formed; but most known forms of clamps must be tightened upon the work by a screw-motion; and the present invention contemplates apparatus which not only obviates the use of weights but is also essentially an adjustable and selflocking clamp which may be employed to apply and to maintain pressure upon an assembly of hat blocks by the simple throw of a lever.

Further the apparatus of the present invention, once adjusted in accordance with the height of a given assembly of hat blocks, may be employed in repeated operations to form hat blanks each like another, and to apply and to maintain a common pressure to all of a series of such blanks.

Further the present invention contemplates hat-blocking apparatus easily adjustable to a variety of heights of hat-block assemblies, so that the apparatus may be conveniently employed to block a number of blanks each of a number of different hat shapes.

Also the apparatus of the present invention is capable of being used to apply and to maintain pressure against a variety of assemblies of hat blocks wherein the uppermost block may or may not be required to be forced toward the lower block or blocks in a vertical direction. This feature is of considerable importance, as will be realized, in edging and otherwise forming the brim or crown of women's hats.

While the invention contemplates apparatus particularly suited to the hat-making industry

2

the same apparatus may be used in reblocking existing hats. The apparatus of the present invention is suited for mounting on such ordinary work surfaces as are common to hat-making and hat-blocking establishments; it may be easily moved about on a work surface or from one work surface to another; and is sufficiently inexpensive so economically a number of such apparatuses may be utilized in a single hat-making or hat-blocking establishment.

These and other objects and advantages will be apparent from the following description and from the drawing, in which Fig. 1 is a side elevational view of an embodiment of the invention, 15 showing an assembly of hat blocks, with a hat blank between them, in that relative position with respect to the apparatus which would obtain immediately after the pressure upon the assembly and blank had been relieved; Fig. 2 is a detail, 20 from the angle of view of Fig. 1, of parts including an adjacent to a self-locking toggle, more particularly described below, showing the toggle unlocked; Fig. 3 is another detail, from the same angle of view, but including additional parts, of 25 the toggle and adjacent elements, showing the toggle in locked position; and Fig. 4 is the section indicated by 4—4 in Fig. 3. Figs. 2, 3, and 4 are double the scale of Fig. 1, and each is partly erased to reduce the figure.

30 With reference now to Fig. 1, which shows the entire apparatus from the side, 1 is a base, which may be conveniently a suitably heavy disk of metal, having an upper planar work surface 2, and, to one side, e. g., the rear, a hub 3 arranged to support vertically a rod 4.

40 A cantilever 5, preferably a substantial block of metal, bored at 6 to receive the rod 4 and to slide up and down thereon, extends outwardly from the rod 4 over the work surface 2; a set screw 7 having a knob 8 to facilitate manual adjustment thereof is provided for the purpose of locking the cantilever 5 at a predetermined height above the work surface 2 on rod 4.

45 Secured to an end plate 9 and to the outer end of the cantilever 5 by means of four screws 10, 10, 10, 10, are two similar U-shaped members 11 and 12, and each has a bent portion arranged to provide a foot to be applied against the end plate 9 and to be engaged by two of the screws 10. Fig. 4 clearly illustrates the method of securing the two U-shaped members 11 and 12 to the end plate 9 and the outer end of the cantilever 5. The bent portions providing feet for the U-shaped members are designated 13 and 14 re-

spectively. The two members 11 and 12 are so mounted on the end plate 9 that the U-shaped portions of each combine to form a single U-shaped bracket extending outward from the end of the cantilever 5 as clearly seen in Figs. 1, 2, and 3.

A pair of nearly half round straps 15 and 16 secured by a rivet 17 to the lower extremities of the U-shaped members 11 and 12 on the outsides of said members carries a suitable bushing 18 (see Figs. 2, 3, and 4) through which is slidably received a vertically disposed rod 19. The rod 19 is drilled and tapped at its lower end to receive a screw 20. A nut 21 serves to lock the screw 20 with respect to the rod 19, and plainly the screw, which is an extension of the rod, may be adjusted effectively to lengthen or shorten the rod. At the lower end of the screw 20 is a ball 22 which is received rotatably within a socket 23 of a bell-shaped element 24 which serves as the member actually to contact the top of an assembly of hat blocks when the apparatus is employed to apply and to maintain pressure thereagainst. The bell-shaped element 24 may or may not be hollow, but the bottom portion 25 thereof is provided with a spheroid surface so that no opening is exposed below, such surface being relied upon to contact a variety of shapes of blocks.

At the upper extremities of the U-shaped members 11 and 12, and on the outside of such members, are pivotally mounted a pair of similar parts 26 and 27. A rivet 28 serves as the common pivotal mounting. The main body of each part (26 and 27) is offset from the point of the pivotal mounting (at 28) so that each part is provided with a heel through which another pivotal mounting (which may be another rivet) passes at 29, and each part is effectively a bell-crank. Each part is bent twice outwardly from the two pivotal mountings so that the flats of the parts are brought in contact to form a lug to be received within a socket in a suitable handle 30.

The upper end of the rod 19 is drilled at 31 to receive a pin, or rivet, 32, which serves as a pivotal mounting upon the upper end of the rod 19 for two yokes 33 and 34, one on either side of said rod, and above the straps 15 and 16. Each yoke connects the upper end of the rod 19 to the pivotal mounting at the heels of the parts 26 and 27, as shown in the figures.

Obviously, as shown particularly in the comparative positional views of Figs. 2 and 3, when the handle 30 is positioned as in Fig. 2 the rod 19 is raised, and when the handle 30 is positioned as in Fig. 3 the rod 19 is lowered, and, consequently, the bell-shaped element 24 is accordingly raised and lowered. The axial shift available in the rod 19 by means of the operation of the handle 30 is of course a constant. It has been shown above how the effective length of the rod 19 may be changed by means of the screw 20, and how the effective uppermost and lowermost positions of the bell-shaped element 24 may be further changed by means of the set screw 7, knob 8, and slidable cantilever 5.

When the handle 30 is positioned upward and backward from the lowermost position as indicated in Fig. 2 it will be understood, of course, that the bell-shaped element 24 hangs freely on the ball 22 of screw 20; but if the handle 30 is brought downward and attains the position of Fig. 3 after the bottom portion 25 of the bell-shaped element 24 is in tension against objects

between itself and the work surface 2, such tension is automatically maintained as the toggle comprising the yokes 33 and 34 is axially centered with the rod 19. To prevent an overthrow of the toggle two lugs 35 and 36 are provided within and to the fore of the U-shaped members 11 and 12, there being one lug on each member, each lug being alike except that each is opposite hand to the other, the extremity of each lug being bent to form a stop for the toggle (as shown in Fig. 3). The bent ends of the two lugs 35 and 36 are seen from the front of the apparatus in Fig. 4. Fig. 4 shows the parts of the toggle in the same position as does Fig. 3.

In blocking a hat blank, for example, the operation of the apparatus is well understood from Fig. 1. On the work surface 2 I show an assembly of blocks, in which 50 designates a bottom-most permanent assembly of blocks operating as a single block and arranged to shape the upper side of a hat blank, and 51 designates an interior crown block. In the figure the forming operation is assumed to be complete. The formed blank, which may be readily followed in the small sectional portion of the figure, is designated as 52, and is shown to be secured to the lowermost permanent assembly of blocks 50 by a cord 53, in the usual manner.

The adjustment shown in Fig. 1 for the cantilever 5 is such as would accommodate the block assembly shown in the drawing. Before the operation which is shown in Fig. 1 to have been completed, the cantilever 5 is properly positioned on rod 4, and locked by means of the set screw 7. The adjustment sought is of course that suitable to the constant throw of the rod 19 with respect to the block assembly to be used. Final adjustment may be made after trial throws of the handle 30 by lengthening or shortening the effective length of rod 19 by means of screw 20. To those skilled in the art it will be understood that the adjustments are made with the bottom block or bottom assembly of blocks free of the hat blank so that the depth of throw of the upper block with respect to the lower block, or assembly, may be properly gauged so that the adjustments may accord therewith.

It will be understood from the foregoing that where one adjustment has been fixed with respect to a given set or assembly of blocks that the apparatus may be employed thereafter to duplicate its initial operation, and to form alike a series of hat blanks of like characteristics.

I claim:

1. In a hat blocking apparatus, a base having a planar upper surface for supporting thereon an assembly of hat blocks, a frame mounted on said base, a rod reciprocable in said frame toward and away from the base, a handle terminating in a bell crank, the inner end of the crank of the said bell crank pivoted to the frame, a link, said link being pivoted at one end thereof to the outer and free end of the crank of the said bell crank and the other end of the link pivoted to the rod, and a bell shaped element mounted on the rod, said link and said bell crank constituting a toggle means for reciprocating the rod in the frame toward the base upon rotating the handle on the inner end of the crank of the bell crank to lock the bell shaped element against a hat block assembly supported on the base and away from the base to unlock the bell shaped element from a hat block assembly supported on the base.

2. The apparatus of claim 1, said rod having

at its lower end a ball, said bell shaped element having a socket for receiving therein the said ball and said bell shaped element having a spheroid bottom for the purpose of translating pressure to a variety of hat block shapes from said rod.

3. The apparatus of claim 1, said frame including a vertically disposed member and a horizontally disposed cantilever slidably secured on the vertically disposed member, said rod reciprocable in the horizontally disposed cantilever.
